INVENTORS

THE NORRIS PETERS CO., PHOTO-LITHO., WASHINGTON, D. C.

UNITED STATES PATENT OFFICE.

THOMAS H. SIMPSON AND PHILIP T. HANDIGES, OF DETROIT, MICHIGAN,
ASSIGNORS TO THE MONARCH BRAKE-BEAM COMPANY, LIMITED, OF
SAME PLACE.

BRAKE-BEAM FOR RAILWAY-CARS.

SPECIFICATION forming part of Letters Patent No. 606,308, dated June 28, 1898.

Application filed January 3, 1898. Serial No. 665,318. (No model.)

To all whom it may concern:

Be it known that we, THOMAS H. SIMPSON and PHILIP T. HANDIGES, citizens of the United States, residing at Detroit, county of Wayne, State of Michigan, have invented a certain new and useful Improvement in Brake-Beams for Railway-Cars; and we declare the following to be a full, clear, and exact description of the invention, such as will enable others skilled in the art to which it appertains to make and use the same, reference being had to the accompanying drawings, which form a part of this specification.

Our invention has reference to a novel brake-beam for railway-cars; and it consists of the device, its construction, combination, and arrangement of parts, as hereinafter described and claimed, and illustrated in the accompanying drawings, in which—

Figure 1 is a front elevation. Fig. 2 is a plan view. Fig. 3 is an end elevation. Fig. 4 is a detail view in perspective, illustrating a modification of the invention. Fig. 5 is a view in section on the line 5 5, Fig. 2. Fig. 6 is a detail view showing the braced fulcrum-jaws. Fig. 7 is a view in section on the line 7 7, Fig. 1. Fig. 8 is a view in section on the line 8 8, Fig. 6. Fig. 9 is a detail view illustrating a modification in the construction 30 of the brake-head.

We carry out our invention as follows:

A represents the body of the beam, preferably made of I-shaped metal. B is a brake-head engaged thereupon, the head being formed, preferably, with an open T-shaped slot or recess (indicated at b) to slip over the end of the I-beam A, said head being secured to the I-beam or body in any suitable manner, as by a bolt b'. We prefer to construct this 40 brake-head with strengthening ribs or braces b² b³, said ribs or braces located at or near the marginal edge of the head, as shown, thereby giving greater firmness and strength to the brake-head.

C represents the fulcrum-jaws, preferably formed of a single integral piece, with an open T-shaped slot or recess C' to slip over the body of the beam, the inner end of said jaws being rigidly secured to the body of the beam

in any suitable manner, as by a rivet or 50 bolt C².

Our invention contemplates the construction of the fulcrum-jaws with arms c² c³, having their outer portions braced to make the arms firm and strong and to prevent breakage. Accordingly c c' represent brace portions of said arms, which may be formed by constructing the arms to project outwardly in a direction toward the recess or slot therein, as shown, the outwardly-projecting braces 60 being formed on the outer surfaces of the two arms c² c³. We design also coring out the inner surfaces of the arms c² c³, as indicated at c⁴ in Fig. 8. By coring out the fulcrum-jaws and forming them in this manner 65 we get a larger surface, and consequently greater strength to resist the strain.

D represents the guide-pins, and D' a clip by which each of the guide-pins may be secured to the body of the beam. In order to 70 provide a simple fastening for the guide-pins, the inner end of each pin is preferably formed with a groove or recess (indicated at d) to engage the outer adjacent edge of the body of the beam, as indicated more particularly in 75 Fig. 5, the clip holding the pin against the adjacent edge of the body of the beam. The clip may be secured to the body of the beam in any suitable manner, as by an I-bolt D² passed therethrough. By recessing or grooving 80 the pin, as indicated at d, to set over the adjacent edge of the body of the beam, the pin is held by a simple form of clip firmly in position.

While we have shown and described an I- 85 shaped brake-beam body, we do not limit ourselves solely to this form of construction, although such form is preferred.

As shown in Figs. 3 and 4, the brake-head is constructed with an orifice O, in which a 90 hook may be engaged in a customary manner. In said figures the orifice extends transversely through the end of the brake-head; but in Fig. 9 the marginal ribs which extend from the center of the head to the outer extremities of the head are shown united toward one of the outer extremities of said ribs or braces by a transverse connecting-rib, the 95

orifice extending longitudinally of the brake-head through said connecting-rib and facilitating the engagement of the customary hook therewith at one extremity of the brake-head.

5. The brake-head is formed with transverse ribs intermediate the extremities of the head, through which the head may be bolted to the brake-beam body, as shown, said transverse ribs being located astride said body.

10. What we claim as our invention is—

1. A brake-head formed with transverse ribs intermediate the extremities of the head through which the head is bolted to the brake-beam body, said head provided with marginal strengthening-ribs extending from said transverse ribs to the extremities of the head, and with an additional rib located toward one of the outer extremities of said head and con-

necting the adjacent marginal ribs or braces, said connecting-rib provided with an orifice 20 extending longitudinally of the brake-head, for the purpose set forth.

2. The combination with a brake-beam body, of a guide-pin, and a clip to engage the pin with the body, the inner end of said pin 25 formed with a slot or recess to engage the marginal edge of said body, substantially as set forth.

In testimony whereof we sign this specification in the presence of two witnesses.

THOMAS H. SIMPSON.
PHILIP T. HANDIGES.
